UNITED STATES PATENT OFFICE.

HEDLEY J. DONAHOE, OF CHICAGO, ILLINOIS.

DESIGN FOR A FENCE-POST.

SPECIFICATION forming part of Design No. 29,316, dated September 6, 1898.

Application filed August 6, 1898. Serial No. 687,990. Term of patent 7 years.

To all whom it may concern:

Be it known that I, HEDLEY J. DONAHOE, a citizen of the United States, residing at Chicago, in the county of Cook and State of Illinois, have invented and produced a new and original Design or Useful Shape for Fence-Posts, of which the following, in connection with the accompanying drawings, is a full, clear, and exact specification.

10 In the said drawings, Figure 1 is a front elevation of a fence-post embodying my design. Fig. 2 is a side elevation thereof; and Fig. 3 is a cross-section thereof on the line 2 2, Fig. 1.

15 The leading features of my design consist of a fence-post whose cross-section has the front side portions A B, arranged at an angle to each other and forming the angular vertical edge C, and the rear flanges D, projecting toward each other and arranged at an angle 20 to the portions A B.

25 The vertical angular edge C is provided throughout its height at short intervals with notches c, which, as shown in Fig. 2, extend backwardly or cut into the side portions A B to a point beyond the apex c' of the inner sides of the portions A B.

30 The side portions A B are arranged at substantially a right angle to each other, and the flanges D are located at substantially a right angle to the portions A B, respectively; but

they are much shorter than the angular portions A B, and their edges, while projecting toward each other, are located at considerable distance apart, so that the post presents the appearance of an open back.

35

The entire post is tapered from bottom to top when viewed from the front, as in Fig. 1, this tapering form being the result of the side portions A B being tapered from bottom to top. The flanges D, however, are also tapered from the point d both upwardly and downwardly. The extreme lower end of the post is beveled or pointed, the bevel being extended from the rear edges of the rear flanges D to the front angular edge C, so as 40 to present a single straight edge E when viewed from the side, as in Fig. 2, and two straight edges E, converging to a point, when viewed from the front, as in Fig. 1.

45 Having thus described my invention, what I claim as new therein, and desire to secure by Letters Patent, is—

The new and original design or useful shape for a fence-post substantially as herein shown and described.

HEDLEY J. DONAHOE.
